ELECTRICAL SHAVING DEVICE

Emil G. Berg, Erie, Pa., assignor to Jet Electric
Shaver Corporation, New York, N. Y., a corpora-
tion of New York

Application February 6, 1950, Serial No. 142,609

2 Claims. (Cl. 30—43)

1

This invention relates generally to shaving devices and in particular, shaving devices of the type which are commonly known as electric dry shavers. This application is an improvement of the disclosure in my patent, No. 2,323,084, dated June 29, 1943.

There are no adjustable means on the head of a dry shaver to prevent the skin from passing through the slots thereof into the path of the cutter teeth. Dry shavers on the market today must design guard members with slots therein of such thickness that the tenderest of skins will not pass therethrough. It is, therefore, necessary to design the heads of these present day dry shavers for the man with the lightest skin texture. A man with a medium or heavy beard or with a heavier skin texture is not able to get a suitable shave with present dry shavers on the market.

It is, accordingly, an object of my invention to overcome the above and other defects in electric dry shavers and it is more particularly an object of my invention to provide an electric dry shaver which is simple in construction, economical in cost, easy to operate, easy to adjust, and which has long life and efficient operation.

Another object of my invention is to provide an electric dry shaver with novel slots in the guard member thereof and with secondary adjustable guard members secured thereon movable over the slotted portion of the guard member.

Another object of my invention is to provide an electric dry shaver capable of adjustment to permit shearing of the hair at different distances from the skin. Another object of my invention is to provide end covers on the ends of the head of a dry shaver to hold the sheared hairs in the head of the shaver until the cutting operations are completed.

Another object of my invention is to provide an electric dry shaver with secondary guard members and means for operating the secondary guard members in unison.

Another object of my invention is to provide an electric dry shaver with secondary guard members, means for operating the secondary guard members in unison, and means for setting and locking the secondary guard members in a given set position.

Other objects of my invention will become evident from the following detailed description, taken in conjunction with the accompanying drawings, in which

Fig. 1 is a plan view of my novel electric dry shaver;

2

Fig. 2 is a side elevational view of my novel electric dry shaver with the end covers for the head in an operative position;

Fig. 3 is a side elevational view of my novel electric dry shaver with the end covers on the head removed for the cleaning of the hairs from the head;

Fig. 4 is a fragmentary side elevational view with parts thereof broken away showing the structure for holding the end covers in position;

Fig. 5 is a perspective view of the spring clip member for holding the end covers in position on the head of my novel electric dry shaver;

Fig. 6 is an enlarged plan view of the primary cutter head of my novel electric dry shaver;

Fig. 7 is a side elevational view of a secondary guard member on the primary cutter head shown in Fig. 6;

Fig. 8 is an end elevational view of the head of my novel electric dry shaver with the secondary guard members disposed thereon;

Fig. 9 is an end elevational view of one of the secondary guard members of my novel electric shaver;

Fig. 10 is a side elevational view of the cam wheel of my novel electric dry shaver for moving the secondary guard members to an open and a closed position;

Fig. 11 is a vertical sectional view taken through the cam wheel shown in Fig. 10;

Fig. 12 is a side elevational view of the cam wheel shown in Fig. 10;

Fig. 13 is a side elevational view of the cam wheel shown in Fig. 10 on the reverse side thereof showing the cam slots;

Fig. 14 is a fragmentary, vertical elevational view showing the spring urged finger for locking the cam member shown in Fig. 10 to lock the guard members in predetermined positions; and

Fig. 15 is a fragmentary vertical sectional view of my novel dry shaver showing particularly the means for locking the cam wheel and secondary guard members.

Referring now to the drawings, I show in Figs. 1 to 15 inclusive an electric dry shaver having a handle formed from mating halves 1 and 2 preferably made of a suitable plastic material. The motor (not shown) of the shaver is conventional and it operates an oscillatable lever 3 (Fig. 15). The outer end 4 of the oscillatable lever 3 is received in a slot 5 formed in a depending portion 6 of a cutter 7. The cutter 7 has outwardly extending guiding ribs or flanges 8 which

engage the inner side of the primary guard member 13 of my novel dry shaver. The cutter 7 has a tooth edged, arcuate portion 14 with V-shaped slots which move in engagement with the underside 14a of the face of the guard member 13 beneath the series of slots 15 (Figs. 6, 7, and 8). The slots 15 may be arranged in staggered relationship as shown in the drawings or they may be aligned one with the other without departing from my invention.

I prefer to form the slots 15 in the primary head 13 with the sides thereof diverging outwardly as shown in Fig. 6. The slots 15 vary in width about ten thousandths of an inch to approximately twenty thousandths of an inch at the outer ends thereof. Thus, when the secondary guard members 16 are moved away from the center line of the primary head 13, the width of the slots 15 provided for cutting hair increases. The slots in the leading edge 18a of the secondary guard members 16 are approximately twenty-five thousandths of an inch in width and they are aligned with the slots 15 over which they move in the primary guard member 13. My novel electric shaving device will operate efficiently without the use of the slots in the slotted portions 18 of the secondary guard members 16 but I prefer to use the aligned slots therein. The opposed secondary guard members 16 on the primary guard member 13 embrace the primary guard member 13 with the slotted edges 18 thereof overlying the portions of the slots 15 in the primary head 13. It will be noted that the arcuate shaped base portion of the primary guard member 13 engaged by the arcuate shaped portion 14 of the cutter 7 is thicker in the center than at the outer edges thereof so that as the secondary guard members 16 move outwardly, the thickness of the base portion of the secondary guard members 16 will decrease to give a closer shave. The arcuate shaped base portion is approximately four thousandths to five thousandths of an inch in thickness at the extremities thereof and approximately fourteen to fifteen thousandths of an inch in the center thereof.

The secondary guard members 16 have a slotted portion 18 with a leading edge 18a which is tapered to a point so as to provide comb teeth for lifting the hair on the face to be shaved. A second, upwardly extending comb portion 18b is also formed on the leading edge portion 18 of the secondary guard members 16 for combing out the hair to be shaved before it is engaged by the opposite leading edged comb 18a. A third comb 18c is provided on the trailing edge opposite to the leading edge 18a of the secondary guard members 16 to provide a further comb for combing out the hair to be engaged by the cutter 7.

The secondary guard members 16 are held in position against the primary guard member 13 by arcuate shaped spring brackets 19 secured to a support 20 by screws 21, the support 20 supporting the primary guard member 13. I have shown the periphery of the cam 26 divided into twenty graduations or divisions 22 so that the secondary guard members 16 may be adjusted to twenty different positions in relation to the slots 15 in the primary guard member 13. It will be evident that any number of divisions may be provided without departing from my invention. The cam wheel 26 is in the form of a frustum of a cone. Arcuate shaped cam slots 25 are formed in the face of the cam wheel 26 as shown in Fig. 13 and the headed ends 24 of the arms 23 extend-

ing from the secondary guard members 16 move therein. Upon rotation of the cam wheel 26, the arms 23 attached to the secondary guard members 16 are moved inwardly and/or outwardly an equal distance in unison thereby moving the secondary guard members 16 around the primary guard member 13 toward or away from each other. The arcuate shaped spring brackets 19 urge the secondary guard members 16 against the primary guard member 13 of the shaver at all times. The portions of the divisions 22 on the cam wheel 26 are visible through a window 90 in upper mating half 1. The cam wheel 26 is engageable by a human finger through the window 90 to rotate same. Recesses 27 are provided on the inner periphery 28 of the cam wheel 26 for engagement by the end 34 of a spring urged finger 29. The finger 29 is attached by means of shafts 30 to a button 32 which extends outwardly from the upper mating half 1 of my novel dry shaver. Coil springs 33 as shown in Fig. 14 urge the button 32 outwardly which in turn urges the end 34 of the finger 29 into locking engagement with one of the slots 27 of the cam wheel 26 thus locking the cam wheel 26 in any desired position.

Longitudinally extending grooves 50 are formed by the mating halves 1 and 2 on opposite sides of my novel shaving device for nesting straight 30 depending ends 52 of end covers 53 for covering the open ends of the member 13 to hold cut hairs therein. The end covers 53 have raised, transversely grooved, finger engaging portions 54 for moving the end covers 53 longitudinally in the grooves 50. The depending ends 52 of the end covers 53 have inwardly extending flanged heads 55 which extend into and move in a slot 56 in the bottoms 57 of the grooves 50 on each side of the shaver. Spaced, inwardly extending, projecting ribs 58 are engaged by the reversely bent portions 59 of a spring bracket 60.

One end of each of the brackets 60 is in the form of a flat spring 62 which engages the heads 55 on the end covers 53 to hold them in position 45 in the slots 50 on each side of the shaver. The end covers 53 are normally in a position covering the ends of the guard member 13 as shown 50 in Figs. 1 and 2. When it is desired to remove the cut hairs in the guard member 13, the raised portions 54 of the covers 53 are engaged by a human finger and pushed forwardly whereupon the depending ends 52 of the end covers 53 extend outwardly from the shaver sufficiently to clear the sides thereof so that they may be rotated to a position as shown in Fig. 3 wherein the hairs may be removed from the head 13. To return the end covers 53 to a position covering the ends of the head 13, it is merely necessary that they be rotated so that the depending end 55 thereof is in longitudinal alignment with the grooves 50 and the heads 55 thereon are pressed inwardly against the force of the spring 62 on the spring bracket 60 and it is then moved longitudinally in the slot 56 in the side of the shaver 60 wherein it is held securely in the grooves 50 on each side of the shaver.

It will be apparent that as the secondary guard members 16 are moved with their exposed edges 18 closer to or farther away from each other, a lesser or a greater portion of the slots 15 will be covered or uncovered. The slots in the secondary guard members 16 are in substantial alignment with the slots 15 in the guard member 13 but they are slightly wider than the slots 15 so that hair may be cut by the slots 15

even though the secondary guard members 16 engage each other.

In the operation of my novel shaving device, the end covers 53 are disposed in a position adjacent opposite ends of the guard member 13 as shown in Figs. 1 and 2. The cam wheel 26 is then rotated by the use of the finger 29 after the button 32 is pressed downwardly so that the end 34 of the finger 29 releases the cam wheel 26. The secondary guard members 16 are moved to a position with the leading edges 18 thereof substantially in engagement with each other as shown in Fig. 8 and shaving is started in this position. It is seldom that the skin of a person is so finely textured or the hair on such a person's face would be so fine as to require my novel shaver in this position. The secondary guard members 16 are then moved outwardly one graduation at a time until the required thickness of the face of the primary guard member 13 is found for proper cutting of the beard and the proper width of slot is found which is the most desirable. After each rotation of the cam wheel 26, the button 32 is released and the finger 29 engages an internal groove 27 on the cam wheel 26 to lock it in a predetermined position by the finger 29 when the desired thickness and width of slot is obtained. Sometimes it is desirable to have a predetermined width and thickness of slot to cut long hairs on the neck and another thickness and width of slot 15 to cut the hairs on the side of a face. This is all determined by a trial and error method on the part of the user of my novel shaver. The comb teeth 18a, 18b, and 18c on the leading edges 18 of the secondary guard members 16 provide several combing surfaces to pull the hairs outwardly from the face so that they may be cut by the oscillating cutter 7. The cutter 7 is moved to and fro by the arm 3 leading to a motor which is conventional.

It will be evident from the foregoing description that I have provided a novel electric shaver of the adjustable type which provides simple means for varying the depth to which the skin extends towards the cutter member through the slots of a primary guard member of a dry shaver thereby providing efficient means for shaving closer to or farther away from the skin as desired, which provides means for twenty or more adjustments to provide slots in the guard member of twenty or more varying widths or thicknesses, which provides means for locking the secondary guard members in a predetermined position on the primary guard member in a number of varied positions, and which provides novel connections for end covers on the end of the cutting head of a shaver to retain hair therein until the shaving operation is completed.

Various changes may be made in the specific

embodiment of my invention without departing from the spirit thereof or from the scope of the appended claims.

What I claim is:

- 5 1. In a device of the type described, a member having a series of slots arranged widthwise thereof and defining a series of relatively thin and narrow cutter bars, a pair of opposed, adjustable, arcuate shaped guards on said member for progressively covering over the end portions of said slots therein, arms extending outwardly from said guards, a cam wheel with indicia on the periphery thereof having cam slots in one side thereof for receiving the ends of said projections of said guards and equally spaced grooves on the inner side of a recessed portion on the opposite side thereof, a case in which said elements are disposed having an opening for inspecting the indicia on the periphery of said wheel, a finger engaging the inner grooved portion of said cam wheel for locking it in a predetermined position, a spring for urging said finger into the inner grooved portion of said cam wheel, and a handle on said finger extending outwardly through an opening in said case whereby it may be manually pressed inwardly to release said wheel from said finger to adjust said guards.
- 10 2. An electrical dry shaver, in combination, a cylindrical head comprising a transversely slotted cylindrical member, adjustable, arcuate shaped, secondary guard members having at their adjacent lateral edges thereof slots to coincide with the slotted portions of said cylindrical member, a cutter member movable internally of the slotted portion of said cylindrical member, arms extending outwardly from said secondary guard members, a cam wheel having cam slots in one side thereof for receiving the ends of said arms for moving said guard members around said cylindrical member and having a recessed portion on the opposite side thereof with teeth on the inner periphery thereof, a case for housing all of said elements having apertures therein, a spring urged finger engaging said internal teeth on said cam wheel extending through an opening in said case and being manually operable from the outside of said case for releasing said cam wheel, and springs for urging said finger into engagement with the internal teeth on said cam wheel to lock same.
- 15 30
- 20
- 25
- 30
- 35
- 40
- 45
